UNITED STATES PATENT OFFICE

ARTHUR E. SMALL, OF CHICAGO, ILLINOIS, ASSIGNOR TO UNION METAL PRODUCTS COMPANY, OF CHICAGO, ILLINOIS, A CORPORATION OF DELAWARE

CAR CONSTRUCTION

Original application filed February 18, 1928, Serial No. 255,449. Divided and this application filed March 21, 1930. Serial No. 437,693.

This invention relates to railway cars, particularly steel cars, which because of their constant exposure to the elements are subject to severe corrosion, especially open top 5 or gondola railway cars, which are used to haul coal or other similar commodities, and has for its object the use of relatively non-corrosive material where the maximum corrosion occurs and a relatively lighter and 10 cheaper material at places less subject to corrosion.

Cast metal is not as susceptible to corrosion as rolled steel or rolled iron and annealed 15 cast metal (malleable iron) is not as susceptible to corrosion as cast steel. Malleable iron is just as strong under compression as ordinary cast metal and almost as strong as rolled steel under tension, therefore, in designing a railway car I prefer to make the load sustaining 20 members of rolled steel and the members subject more to the action of corrosion of cast metal, preferably malleable iron, or other relatively non-corrosive material.

Steel or iron which has been rolled flat into 25 plates and subsequently bent, stretched or otherwise deformed is more subject to corrosion than flat rolled steel or iron plates, therefore, I prefer to substitute malleable or other cast metal structures in place of bent steel 30 plates when such bent plates are abnormally subject to corrosion; for instance, corner pieces between the vertical walls and the floor of a railway car.

In the drawings: 35 Fig. 1 shows a typical application of my invention to a railway car.

Fig. 2 shows a modified form.

The right hand side of Fig. 1 is an elevation 40 of an end of a railway car and the left hand side thereof is a cross section of the same car.

The car comprises a side wall steel plate 2; a top side chord 3; a side sill 4; center sill 10; top cover plate 11; bottom plate 12 and 45 side stake 13.

In the car illustrated in Fig. 1 the floor 20, which is subjected to considerable corrosion, is made of wood extending substantially from side to side of the car, and in 50 order to protect the side sill 4 of the car from

moisture penetrating through the floor causing corrosion of this side sill, I provide a cast metal member having a substantially horizontal portion 21 overlying the side sill 4 so as to protect it from the lading. This cast 55 metal member also has an integral substantially vertical portion 22 forming a part of the side wall of the car. This vertical portion extends upwardly any convenient distance and the rolled steel side wall sheet 2 is secured 60 to this upper margin and preferably overlaps it on the inside of the car, as shown.

The wooden flooring 20 preferably overlies and rests upon the horizontal portion 21 of the cast metal member and the cast metal 65 member preferably covers the entire upper surface of the side sill 4.

The side stake 13 is secured to the side sill 4, portion 22 and wall sheet 2 so that all these 70 elements reinforce each other to form a rigid structure, therefore, such a cast metallic member performs the dual function of increasing the resistance of the car wall to corrosion where corrosion is greatest and to strengthen the car wall where greater 75 strength is required.

Fig. 2 shows the invention applied to a gondola car wherein the floor comprises a plurality of hinged doors 30 (hinge not shown). In this figure the malleable iron 80 member 31 has an oblique portion to shed the load and chute it toward the opening.

The invention may be used in either or 85 both the side and end walls of railway cars and any type of railway car, such as box, stock, hopper, etc., as well as gondola cars. The right hand of Fig. 1 shows the vertical portion 22 of the cast metal member extended around the corner of the car (14) to form 90 a part of the end wall 15 of the car. The striking casting 16 is secured to the vertical portion of this end member.

The accompanying drawings illustrate the 95 preferred form of the invention, though it is to be understood that the invention is not limited to the exact details of construction shown and described, as it is obvious that various modifications thereof, within the scope of the claims, will occur to persons 100 skilled in the art.

This is a division of my co-pending application Serial No. 255, 449, filed February 18, 1928.

I claim:

5. 1. In a railway car, the combination of a rolled steel sill, a cast metal member having a substantially horizontal portion overlying the sill so as to protect it from the lading, and an integral substantially vertical portion 10 forming a part of a wall of the car.
2. In a railway car, the combination of a rolled steel sill, a cast metal member having a substantially horizontal portion overlying the sill so as to protect it from the lading, an 15 integral substantially vertical portion forming a part of a wall of the car, and a wooden flooring overlying said horizontal portion of the member.
3. In a railway car, the combination of a 20 rolled steel sill, a cast metal member having a substantially horizontal portion overlying the sill so as to protect it from the lading, an integral substantially vertical portion forming a part of a wall of the car, a wooden flooring overlying said horizontal portion of the member, and a rolled steel wall sheet secured to said member.
4. In a railway car, the combination of a 25 rolled steel sill, a cast metal member having a substantially horizontal portion overlying the sill so as to protect it from the lading, an integral substantially vertical portion, a wooden flooring overlying said horizontal portion, a rolled steel wall sheet secured to said member, and a stake secured to the sill, member and wall sheet.
5. In a railway car, the combination of a 30 rolled steel sill, a door opening, and a cast metal member having a substantially horizontal portion overlying the sill so as to protect it from the lading, and an integral substantially vertical portion forming a part of a wall of the car, said member having an oblique portion forming a chute toward said 35 opening.
6. In a railway car, a vertical wall and a floor, said wall comprising a rolled steel upper portion, a rolled structural steel beam, and an intermediate cast metallic member 40 secured to said upper portion and to said beam, said member having a substantially horizontal flange overlapping the beam and underlying the floor of the car.
7. In a railway car, the combination of a 45 structural sill of relatively corrosive material, and a member of relatively non-corrosive material having a substantially horizontal portion overlying the sill so as to protect it from the lading and a substantially vertical portion forming a part of the load retaining means of the car.
8. In a railway car, the combination of a 50 structural sill of relatively corrosive material, and a member of relatively non-corrosive material having a substantially horizontal portion 55 overlying the sill so as to protect it from the lading and a substantially vertical portion forming a part of the load retaining means of the car.
9. In a railway car, the combination of a structural sill of relatively corrosive material, a member of relatively non-corrosive material having a substantially horizontal portion overlying the sill so as to protect it from the lading and a substantially vertical portion, a flooring overlying the horizontal portion of the member, and a wall sheet of relatively corrosive material secured to said member. 70
10. In a railway car, the combination of a structural sill of relatively corrosive material, a member of relatively non-corrosive material having a substantially horizontal portion overlying the sill so as to protect it from the lading and a substantially vertical portion, a flooring overlying the horizontal portion of the member, and a wall sheet of relatively corrosive material secured to said member. 75
11. In a railway car, the combination of a structural sill of relatively corrosive material, a door opening, and a member of relatively non-corrosive material having a substantially horizontal portion overlying the sill so as to protect it from the lading and a substantially vertical portion forming a part of the load retaining means of the car, said member having an oblique portion forming a chute toward said opening. 80
12. In a railway car, the combination of a member of relatively non-corrosive material having a substantially horizontal portion and a substantially vertical portion, a flooring overlying the horizontal portion of the member, and a wall sheet of relatively corrosive material secured to said vertical portion of the member. 85
13. In a metal wall structure for cars, having a top plate and sill, the combination with a sheet metal panel secured along its upper edge to the plate and terminating at its lower edge above the sill; of a longitudinally extending casting secured to the lower edge of the panel and to the sill, said casting having a web section extending downwardly and inwardly from the sheet metal panel. 90
